MANDARIN CHESSBOARD

Norman Chan, Elmhurst, N.Y., assignor to
A.C. International Corp., New York, N.Y.

Filed June 16, 1972, Ser. No. 263,526

Term of patent 14 years

Int. Cl. D21—01

U.S. Cl. D34—5 SS

The figure is a plan view of a mandarin chess board embodying my new design.

The board is of conventional thickness.

I claim:

The ornamental design for a mandarin chessboard, substantially as shown and described.
